CALCULATOR

Frederic A. Wardenburg and Ralph L. Dodge,
Wilmington, Del.

Application August 2, 1939, Serial No. 287,880

3 Claims. (Cl. 235—88)

This invention relates to calculators for rapid and accurate determination of the time of occurrence of various natural phenomena, which regularly manifest themselves at definitely predetermined times, such as tides, tidal currents, rising and setting of the sun, moon or stars.

Although the time schedules of these phenomena at specified reference points on the earth's surface are published in advance by agencies of the United States Government and by agencies of the governments of other countries, the customary arrangement of these data in tabular form does not lend itself readily to rapid and convenient selection for other points than the tabulated reference points.

It is an object of this invention to overcome the disadvantages outlined and to provide a calculator which presents in compact form the data relating to a single phenomenon over a definite period of time and for a multiplicity of points on the surface of the earth. Our novel arrangement permits rapid calculation of the correct time of occurrence of a phenomenon for selected locations and dates.

Other objects and the basis of construction of the calculators as well as the advantages of the arrangement thereof will become apparent from a consideration of the description following, taken in connection with the accompanying drawings illustrating the complete calculator, Fig. 1, and its two component parts, the front, or "place," disk, Fig. 2, and the back, or "time," disk, Fig. 3. For purposes of illustration and because of its preferred usage therefor we have deliberately restricted our description and illustration to a tide calculator, but it will be evident to one skilled in the art that calculators for other phenomena, the times of which can be predetermined with certainty, are also susceptible to construction by the same principle, and our description does not limit our invention to the tide calculator herein described.

Each calculator consists of two circular disks of suitable materials, such as "Plastacele," cardboard, wood, etc., of such relative dimensions that when one of the disks is superimposed concentrically on the other, the edge of the back disk, Fig. 3 will extend beyond the edge of the front disk, Fig. 2, for some convenient distance, preferably, but not necessarily, one-half inch.

The peripheral portion 7 of the back disk, which is thus exposed around the outside of the front disk, is divided arcuately by radial markings into equal intervals, representing intervals of time. The total number of equal divisions

5 around the ring 1 must be at least equal to the number of hours of the civil day in which the phenomenon for which the calculator is being constructed is known to occur. For the sake of precision in calculation, the number of divisions may exceed this minimum. In the case of the tide calculator, the number of equal division in the time ring must be at least twenty-four, since the tidal phenomenon may manifest itself by highs and lows at any time of the twenty-four hours of the civil day. The time ring 1 of the tide calculator, may be further subdivided, for convenience, into equal time intervals, representing single or multiple minute intervals. In the accompanying illustrations, Figs. 1 and 3, the time ring 1 is divided into twenty-four equal hourly intervals, and each hour interval is further subdivided into twelve equal five minute intervals. The hourly markings are numbered in consecutive order, preferably in accordance with the customary time system, for example, from 12 midnight through 1 a. m., 2 a. m., etc., to 12 noon, and continuing from 12 noon through 1 p. m., 2 p. m., etc., to 12 midnight. The numbering 0 (midnight) to 23 could be employed without departing from the spirit of our invention.

10 If the phenomenon for which the calculator is being constructed were known to occur only between definite limiting hours of the civil day, like the rising of the sun, the time ring, or a portion thereof, may be divided into a number of equal hourly intervals corresponding to the number of hours between the earliest rising and latest rising, thus obtaining the longest possible unit time arc for any given mean diameter of time ring, a desirable, but not required, feature of the calculator.

15 The area of the back disk, inside the time ring, is divided into a number of inner rings 2 each concentric with the time ring 1.

20 Each inner ring contains a series of numbers representing dates, so spaced around the inner rings that when any single date is disclosed centered in a date hole 3 of the concentrically superimposed front disk, Fig. 2, the arbitrarily located reference index 4 on the front disk will point to the time on the time ring 1 at which the phenomenon will occur at the reference place on the date appearing centered in the date hole.

25 On the drawings, illustrating the place disk (Fig. 2), the date holes are represented by small four-sided black areas 3. For convenience in use, the date holes are arranged in columns, one column for each aspect of the phenomenon for

which the calculator is being constructed. In the case of the tide calculator, one column 5 contains the date holes for high tide and the other column 6 contains the date holes for low tide. This columnar arrangement of holes is an advantageous and preferred but not absolutely necessary feature of our invention. The radial distances of the date holes from the axis 7 of the calculator must correspond to the radii of the respective date rings on the time disk.

Each date hole may carry, on an extension of its arc, a designation 8 of the month and days thereof that appear on the corresponding date ring. This designation is also an advantageous and preferred but not absolutely necessary requirement of our invention.

The arbitrarily located reference index 4 is drawn as a radius, to the circumference of the front disk and is labeled by the name of the geographic reference point for which the data have been predetermined. Other indicia for subordinate geographic points 9 are drawn radially on the front disk at angular distances from the reference index equal, respectively, to the predetermined time intervals between the occurrence of the phenomenon at the geographic reference point and its occurrence at the subordinate geographic points. The number of subordinate points that can be included on a single calculator is limited only by the legibility of the names and the availability of the time interval data. The indicia for subordinate stations at which the time of occurrence is later than at the reference station must be on the side of the reference index corresponding to a later time on the time ring 1 and similarly the indicia for subordinate stations at which the time of occurrence is earlier than at the reference station must be on the side of the reference index corresponding to an earlier time on the time ring 1.

For convenience in use the two disks, which together constitute a calculator, are fastened together by a pivot at the center 7 of the two disks, so that the front disk can be rotated concentrically relative to the back disk. If it is desired to represent on a single calculator two phenomena, the two time-date disks can be drawn or printed on the two sides of a single sheet of suitable material and the two separate place disks can be fastened on the opposite sides of the time disk by a single pivot at the center of the three disks, so that the three disks can be rotated concentrically relative to one another.

Although the calculator illustrated herein, Fig. 1, is deliberately constructed to cover a period from May 1, 1939 to September 30, 1939, inclusive, it will be apparent that a longer or shorter period can be covered on a single calculator by increasing the number of inner rings and date holes or by including a longer interval on each date ring, without departing from the spirit of our invention. A calculator for an entirely different period can be constructed on the same principle as the calculator illustrated by properly selecting the relative arcuate locations of the indicia, date holes and dates.

The construction of the calculator, as described herein lends itself to the convenient presentation of data on other phenomena such as

rising of the sun, setting of the sun, rising of the moon, setting of the moon, meridian transit of celestial bodies, time of tidal currents, etc., all of which fall within the spirit and scope of our invention as defined in the following claims.

We claim:

1. A calculator adapted by spatial arrangement to show the precalculable relationships between time, date, place, and appearance of specific phenomena, comprising front and back circular disks, arranged concentrically in a superimposed order and adapted to permit relative rotative adjustment, said back disk having a ring adjacent to the periphery and projecting beyond the front disk and being divided arcuately into equal, consecutively labeled intervals representing time; said back disk having in addition a series of concentric inner rings, each inner ring bearing numbers representing dates; said front disk being perforated by holes whose radial distances from the center of the front disk are, respectively, equal to the radial distances of the inner rings from the center of the back disk and which are adapted to disclose, through the holes, successively, by rotation, the dates in the corresponding inner rings of the back disk; said front disk bearing in addition, radial indicia terminating at the circumference of said front disk and being spaced arcuately to represent tidal time intervals between geographic locations; said indicia being so located with respect to the holes that the indicia will point to the times on the time ring of the back disk at which a tidal phenomenon will occur at the respective geographical locations on the date appearing centered in any date hole.
2. A calculator adapted by spatial arrangement to show precalculable relationships between time, date, place and appearance of specific phenomena, comprising front and back circular disks, arranged concentrically in a superimposed order and adapted to permit relative rotative adjustment, said back disk having a ring adjacent to the periphery and projecting beyond the front disk and being divided arcuately into equal, consecutively labeled intervals representing time; said back disk having in addition a series of concentric inner rings, each inner ring bearing numbers representing dates; said front disk being perforated by holes whose radial distances from the center of the front disk are, respectively, equal to the radial distances of the inner rings from the center of the back disk and which are adapted to disclose, through the holes, successively, by rotation, the dates in the corresponding inner rings of the back disk; said front disk bearing in addition, radial indicia terminating at the circumference of said front disk and being spaced arcuately to represent time intervals between the appearance of a celestially determined natural event at different geographical locations, said indicia being so located with respect to the holes that the indicia will point to the times on the time ring of the back disk to which the celestially determined natural event will occur at the respective geographical locations on the date appearing centered in any date hole.
